CLAIM

The ornamental design for a security bag as shown and described.

DESCRIPTION

FIG. 1 is a front view of a security bag showing my new design;

FIG. 2 is a rear view of the security bag;

FIG. 3 is a left side view of the security bag;

FIG. 4 is a right side view of the security bag;

FIG. 5 is a top view of the security bag;

FIG. 6 is a bottom view of the security bag; and,

FIG. 7 is a top front side perspective view of the security bag.

The broken lines in the drawing figures are illustrative of stitching forming no part of the claimed design.
